(57) **CLAIM**

The ornamental design for a saw handle, as shown and described.

DESCRIPTION

FIG. 1 is a left perspective view of a saw handle;
FIG. 2 is a right perspective view thereof;
FIG. 3 is a left side planar view thereof;
FIG. 4 is a right side planar view thereof;
FIG. 5 is a top view thereof;
FIG. 6 is a bottom view thereof;
FIG. 7 is a back view thereof; and,
FIG. 8 is a front view thereof.
The lines shown in phantom are for illustrative purposes only, and do not form any part of the invention.
